UNITED STATES PATENT OFFICE.

OTTO J. BORK, OF SUN PRAIRIE, WISCONSIN.

MILKING-MACHINE WASHING DEVICE.

Application filed November 6, 1925. Serial No. 67,414.

To all whom it may concern:

Be it known that I, OTTO J. BORK, a citizen of the United States, residing at Sun Prairie, in the county of Dane and State of Wisconsin, have invented certain new and useful Improvements in Milking-Machine Washing Devices, of which the following is a specification.

This invention relates to a washing device for use in connection with milking machines, and has for its object to provide, in a manner as hereinafter set forth, a device of the class referred to for cleaning the lead and tit cups of a milking machine to keep them fresh and in sanitary condition.

Further objects of the invention are to provide, in a manner as hereinafter set forth, a washing device for the purpose referred to which is simple in its construction and arrangement, strong, durable, compact, thoroughly efficient and convenient in its use, and comparatively inexpensive to manufacture.

With the foregoing and other objects in view, the invention consists of a novel construction, combination and arrangement of parts as hereinafter more specifically described and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a top plan view of a washing device in accordance with this invention.

Figure 2 is a section on line 2—2, Figure 1.

Figure 3 is an inverted plan view of the device.

Referring to the drawings in detail, a washing device in accordance with this invention, comprises a receptacle which is referred to generally by the reference character 1 and which constitutes a water container. The receptacle 1 consists of a body portion formed of an upper annular section 2 and a lower flaring section 3. The top of the section 3 is provided with a laterally extending annular flange 4 which is angle-shaped in cross section and provides a seat for the bottom of the section 2, as well as overlaps the periphery of the section 2 at the bottom 2. The section 2 and flange 4

are suitably secured together. The lower end of the section 3 is formed with a laterally extending annular flange 5 and abutting thereagainst, as well as overlapping said flange 5, is a circular plate 6, which forms the bottom of the receptacle 1. That portion of the plate 6, which overlaps the flange 5 is indicated at 7. The flange 5 and the plate 6 can be secured together by any suitable means. Secured to and extending within the section 2 of the receptacle 1, at the top thereof, as well as depending within said section, is a top member 8, which is in the form of an annulus and which prevents splashing when water is supplied to the receptacle 1. The upper section 2 of the receptacle 1, is provided with a pair of diametrically opposed handle members 9.

The plate 6, which provides the bottom of the receptacle 1, is formed with a series of spaced openings 10 and the material surrounding each opening is offset as at 11 to provide a flaring collar and into each of said collars is extended the upper end of a tapered coupling tube 12, which is employed for connecting the lead or a tit cup to the receptacle 1, and as illustrated in Figure 2, the tubes 12 have leads 13 connected therewith and said leads are in the form of rubber tubes that extend from the tit cups to the pulsator. Each of the tubes 12 is secured at its upper end by any suitable means to the plate 6.

When the device is used, the end of each lead that is disconnected from the pail or pulsator is placed upon one of the tubes 12. Water is then supplied to the receptacle 1 and flows through the lead and tit cup and discharged at any desired point. This affords a very convenient, practical and sanitary way of cleaning the leads and keeping them fresh.

It is thought that the many advantages of a washing device, in accordance with this invention, and for the purpose referred to, can be fully understood, and although the preferred embodiment of the invention is as illustrated and described, yet it is to be understood that changes in the detail of construction can be had which will fall within the scope of the invention as claimed.

What I claim is:—

1. A washing device for the purpose set forth, comprising a container adapted to have water supplied thereto and further having its bottom formed with a plurality

of openings, and a tapered tube secured in and extending from each of said openings and adapted to have detachably mounted thereon the lead of a milking machine for the purpose of cleaning the lead on the supply of water to the container.

2. A washing device for the purpose set forth, comprising a container adapted to have water supplied thereto and consisting of a body portion having the lower part thereof flaring, said body portion further having its bottom formed with a plurality of openings, and a coupling tube having its upper end secured in each of said openings, said tubes depending from said openings and each adapted to have detachably connected thereon a lead of a milking machine for the purpose of cleaning said lead when water is supplied to the container.

3. A washing device for the purpose set

forth, comprising a container adapted to have water supplied thereto and consisting of a body portion having the lower part thereof flaring, said body portion further having its bottom formed with a plurality of openings, a coupling tube having its upper end secured in each of said openings, said tubes depending from said openings and each adapted to have detachably connected thereon a lead of a milking machine for the purpose of cleaning said lead when water is supplied to the container, and a top member mounted on and depending into said body portion and formed of an annulus providing means to prevent splashing when the water is supplied to the container.

In testimony whereof, I affix my signature hereto:

OTTO J. BORK.
